OCCIPITAL PATIENT SUPPORTING DEVICE

Roger Anderson, Seattle, Wash.

Application July 26, 1949, Serial No. 106,953

4 Claims. (Cl. 128—71)

1

My invention relates to an occipital patient supporting device for application of a plaster or a plaster cast. More particularly, my invention relates to a cup-shaped support for the back of the head of a patient, which cup-shaped support is connected at an end portion with an arm so that the head of a patient may be supported during the application of a plaster or a plaster cast which includes a head cast, and the cup-shaped support member can be removed, after the cast has been completed, and out through the opening in the cast which is generally left at the top of the cast.

My invention is a continuation, in part, of my co-pending application entitled "Orthopedic Table and Fracture Reducing Apparatus," Patent No. 2,477,562, filed October 17, 1945, issued August 2, 1949 (hereinafter referred to as my orthopedic table patent).

While my present invention may be used in connection with other orthopedic tables than that illustrated in my said orthopedic table patent, for purposes of illustration and to better understand the present invention, the same, by way of example and not by way of limitation, will be explained and illustrated in connection with the orthopedic table of said patent and without unnecessary detailed consideration of the said orthopedic table.

A plastic or a plaster cast for the head of a patient or a head cast for a patient, as the terms are used herein, include casts which include the head of the patient and the cast may extend to include the upper chest of the patient and even more of the patient. Such head casts normally include within the cast all the patient's head except the patient's face and the top of the patient's head, and also include the neck of the patient, and the upper trunk of the patient.

In the prior art of applying such head casts to patients, one procedure was to support the head of the patient by a suitable rest until the cast had been extended over the upper chest of the patient, the neck of the patient, and part of the patient's head. Then the rest for the patient's head was removed and the patient's head was manually supported and manipulated by assistants during the application of the head portion of the cast. In case of a patient with sufficient hair on the head, such as with a woman, the hair was utilized as a means to be grasped so the neck and head could be angularly positioned and at the same time tension could be applied. Difficulties involved in this technic include: angular corrective adjustments of the neck of the patient were difficult to precisely achieve and to maintain; de-

2

sired traction on the neck of the patient was difficult to attain and maintain; and precision results were not often obtained because of the personal element involved in the manual adjustment and maintenance of the relative position of the head and neck of a patient by an assistant.

Another prior art practice was to employ a narrow board or slat to support the backbone and head of the patient. Such boards or slats generally extended from the pelvic area to the head of the patient and such boards were supported at opposite end portions. Obviously, the boards were non-conforming to the contour of the back of the patient and non-conforming casts, particularly around the neck area, were very common.

Another prior art practice often employed in the attempt to properly position the head and neck of a patient during the application of a head cast involved the use of slings and bandages. In such instances generally a sling was used to obtain desired tension and bandages were employed to angularly dispose the head and neck of a patient to obtain desired positions and angular corrections. Normally when slings and bandages were so used the patient was placed in a sitting or standing position as these were deemed the most suitable positions to obtain most accurate results. Difficulties involved in this technic include: the patient must be in such physical shape and not anaesthetized so the patient can cooperate during the application of the cast; such technic required several trained assistants as well as the surgeon in charge of the operation; any angular corrections of the neck and head are exceedingly difficult to obtain and to maintain; and resultant shock or extreme discomfort to the patient which usually obtains because of such technic.

While other technics have been employed to support and position the head and neck of a patient during the application of a head cast, the two mentioned examples will illustrate standard prior art practices and some of the difficulties obtaining.

The above-mentioned, and many other, difficulties are overcome by my inventions herein as the patient, with my said inventions, may be supported in a supine position with the occiput disposed in a cup-shaped support and with the patient mechanically held and maintained in a desired position, and then the head cast may be applied over the occipital supporting means while the position of the patient is so maintained, and after the completion of the cast the occipital sup-

port and supporting arm therefor may be removed from within the cast by angularly moving the occipital support following the contour of the head of the patient until the occipital support is moved out of the cast through the normal opening left at the top of the cast.

The above-mentioned general objects of my invention, together with others inherent in the same, are attained by the devices illustrated in the accompanying drawings, throughout which like reference numerals indicate like parts:

Figure 1 is a view in side elevation of an orthopedic table in connection with which is employed the occipital support means of this invention;

Fig. 2 is a fragmentary detached plan view on a larger scale, illustrating generally a frame means shown in Fig. 1, and taken substantially on broken line 2—2 of Fig. 1;

Fig. 3 is a detached fragmentary view on a still larger scale, partly in elevation and partly in section and taken substantially on broken line 3—3 of Fig. 1, of an occipital support embodying the present invention and illustrating supporting means therefor;

Fig. 4 is a fragmentary view (somewhat similar to the right end portion of the structure shown in Fig. 1 of the drawings) on a larger scale than Fig. 1, and showing a modified form of the present invention;

Fig. 5 is a fragmentary view showing parts indicated in Fig. 4, on a larger scale than Fig. 4, and illustrating by full line and dash line positions the manner in which the occipital support is removed after the head cast has become sufficiently set or hardened so that the occipital support may be removed;

Fig. 6 is a detached perspective view of an occipital support embodying this invention; and

Fig. 7 is a fragmentary plan view illustrating a position which the parts shown in Figs. 4 to 6 inclusive may assume.

While my present invention may be employed with other orthopedic tables, by way of illustration and as an explanation of such invention, the same is illustrated and will be described in connection with the table of my said orthopedic table patent. Thus legs 7 having downturned end portions 8, provide a suitable supporting base.

Preferably the upper structure of the fracture table carried by the base 7—8 is adjustably movable relative to such base structure both for vertical and tilting movements. The housing structure to include the mechanism to adjust the upper structure of the fracture table may include a rectangular box-like base 9, which is supported by bars 10. Two hydraulic cylinders 11 and 12 are secured to the box-like base 9 and extend upwardly therefrom. Suitable pistons are provided in the respective cylinders 11 and 12 and said pistons are connected by pivot members 13 and 14 with a mounting block 15. The said hydraulic means may be operated by four pedals 16, 17, 18 and 19 and such pedals are responsive to the lower extremities of the operator, such as the operator's feet. Various desired movements of the upper structure of the table can be controlled by suitable manipulation of the foot pedals 16 to 19, inclusive.

The mounting block 15 carries two transversely spaced apart tubular horizontal socket members 20 (only one of which shows in Fig. 1) that are adapted to telescopically receive and support two parallel extension frame tubes 21 (both of which are shown in Fig. 2). The outer ends of the tubes 21 are secured to a bracket member 22.

The extension frame provided by tubes 21 and bracket 22 is adapted to support a plurality of different devices that contribute to the utility of the fracture table, including the supporting of the occipital support of this invention and the supporting of devices which cooperate therewith.

A lead screw 24 (Fig. 2) is provided to longitudinally adjust the extension frame 21—22. One end portion of the lead screw 24 is threaded into the mounting block 15 and the other end portion thereof extends into gear box 25 so that upon turning of crank 26 shaft 27 may be angularly moved and in turn the lead screw 24 may be angularly moved.

The bracket member 22 is provided with a plurality of openings 28, 29, 30, 31, 32, 33 and 34, into which are inserted tubes to support various appliances from the bracket member 22.

20 In my said orthopedic table patent and in my co-pending application for an inter-scapular supporting device, Serial No. 106,954, filed July 26, 1949, these various openings and the parts 7 to 27 herein, are more fully disclosed and described.

25 Preferably the openings 30, 31, 32 and 34 are provided with a keyway slot 37 so that shafts with a mating key or pin may be inserted in said openings and held against angular movement.

30 Traction frames 40 (left hand end portion Fig. 1) comprise tubular members 41, which telescopically interfit with removable tubular members 42. The inner ends of the tubular members 41 are rigidly secured to a yoke 43, which is substantially U-shaped in plan. The yoke 43 carries a rack member 44 which is mounted for longitudinal sliding movement in a housing member 45. Within the housing member 45 are suitable worms and gears so as to provide for longitudinal movement of the rack 44 in opposite directions in response to movement in opposite directions of the crank means 46.

35 The housing member 45 is secured by bolt means 47 to a bracket 48. Bracket 48 is pivotally connected with a bracket 49 and is mounted for pivotal movement as respects the same on a vertical axis. The bracket 49 is rigidly connected with mounting block 15. Again the details of construction of parts, including parts 37 to 49, inclusive, is best shown in my said orthopedic table patent and thus no further detailed description of said parts is given herein.

40 The removable tubular members 42 carry a bracket 50. The purpose of such bracket 50 is to provide means which may be secured to the feet of a patient and thus to provide for traction or counter-traction on the feet of a patient. Thus bracket 50 is preferably detachably and adjustably connected to the tubular members 42 by split sleeves 51 and locking screws 52. By loosening a locking screw 52, each of the sleeves 51 may be longitudinally adjusted relative to a tubular member 42.

45 Preferably, leg boards 53 are provided for supporting the legs of a patient and such leg boards may be angularly and vertically adjusted by means of threaded shafts 54 and 55. In order to provide for desired angular movement, one of the shafts 54 or 55, such as each shaft 55, is connected with the leg board 53 by means of cross pin 56 and slot 57. Thus leg board 53 may be tilted as well as vertically adjusted so that said leg board is either horizontal or is at an incline to the horizontal and either end may be 50 higher than the other, and sufficient movement

is provided to accomplish such purpose by reason of the cross pin 56 movable in a general horizontal direction in the slot 57. The shafts 54 and 55 extend downwardly through carriage housings 58 and 59, respectively. Carriage housings 58 and 59 are supported and preferably releasably locked to tubular members 42 and 41.

The trunk of a patient may be supported by an inter-scapular support or rest 60 which, in turn, may be supported by a tubular member 61 carried by bracket 22. A threaded shaft 62 telescopically and threadedly interfits with tubular member 61 and relative angular movement between said tubular member 61 and shaft 62 may be prevented as by pin means 63 carried by shaft 62, which pin means 63 interfits with a longitudinal slot in the tubular member 61. This construction may be identical with the construction shown in Fig. 3, wherein pin 63 is carried by threaded shaft 68 and slot 64 is disposed in tubular member 66 for supporting the occipital support of the present invention. Hence the details regarding the pin 63 and the slot 64, so far as the inter-scapular support is concerned, are not illustrated in detail herein. Nut means 65 is threaded on shaft 62 to adjust the elevation of the inter-scapular support 60, all of which is shown more in detail in my said co-pending application for an inter-scapular supporting device. The use of this inter-scapular supporting device 60 is closely allied with the occipital support of the present invention in that they are often used together. Whenever a head is to be supported for the application of a cast, generally a chest is likewise to be supported as most head casts extend down over the chest area. As both devices are of a nature where a patient may be supported and a cast applied about the supporting devices, their association in use will become apparent.

In the form of my present invention as shown in Figs. 1 to 3, I provide tubular member 66 carried by bracket 22 and more particularly in hole 30 of said bracket. By reason of the keyway 31 and a key or pin carried by tubular member 66, angular movement of the tubular member 66 is prevented. A nut 67 is threaded on shaft 68 and shaft 68 is telescopically received within tubular member 66. Tubular member 66 is provided with a longitudinal slot 64 and shaft 68 is provided with a pin 63 slidable therein to prevent relative rotary movement between tubular member 66 and shaft 68. Obviously, shafts having squared or other patterned portions and mating patterns in the tubular members may be employed in lieu of the pin and slot means described in connection with tubular member 66 and shaft 68. The shaft 68 supports an L-shaped bracket 69 (Figs. 1 and 3) which, in turn, supports a cup-shaped head rest 70, and the said head rest 70 and L-shaped bracket 69 are preferably detachably connected with said shaft 68 by reduced end portion 85 which is rotatable in a recess in bracket 69. Any desired angular adjustment of bracket 69 may be maintained by set screw 81.

An extension member 71 is suitably connected with the bracket member 22 as by bolt and nut means 72 operating in opening 34 in bracket 22, and stud 73 operating in opening 33 in said bracket 22. Extension member 71 carries an upright post 74, which upright post carries threaded shaft and nut means 75. The threaded shaft and nut means 75 are mounted on post 74 preferably so the shaft will not rotate but can be moved horizontally by rotary movement of the nut means 75. The end of the threaded shaft 75

toward the patient carries a hook member 76 which, in turn, may be connected to a head sling 77.

In the event that tension is placed on the head of the patient through head sling 77, countertraction may be placed on the feet of the patient by structure illustrated in my said orthopedic table patent. Generally, said structure (upper left hand portion of Fig. 1) comprises a threaded shaft 78 and a nut means 79 which are supported for longitudinal movement by the bracket 50 so that the threaded shaft 78 may move longitudinally but will not turn relative to the bracket 50. The inner end of the threaded shaft 78 supports a bracket 80 which, in turn, supports a foot plate 81. Strap means 82 are wrapped about each foot of a patient and thus connect each foot of a patient to a foot plate 81.

In the foregoing description the various parts here illustrated and described have been illustrated and described more fully in my said orthopedic table patent, of which the present application is a continuation-in-part, and hence many of the details which show one operative environment of the present invention have not been fully described and illustrated in detail in the interest of brevity.

In general it may be stated that a patient can be supported at the buttocks on sacral rest 83 and maintained there by the leg boards, or foot plates, etc. The trunk and intermediate portions of the body are supported by the inter-scapular support 60 and the head is supported by the head rest 70 and thus a cast can be applied, when desired, about the head rest 70 as well as the inter-scapular support 60, and said supports can be later removed from the cast after the cast has sufficiently set or hardened.

In Figs. 4 and 5 of the drawings, I have shown a modified form of the head rest wherein the head rest is still supported by a tubular member 66 from the bracket member 22. Also in Figs. 4 and 5 of the drawings there is illustrated threaded shaft 93 and connector 94 which is mounted for angular movement on shaft 93 and any adjusted position can be maintained by reason of screw 95 having a suitable and readily engageable wing nut thereon. An opening is provided in the connector 94 to slidably receive bar 96. Screw 97 with a suitable wing nut head thereon adjusts any desired relative position between the connector 94 and the bar 96 (see also Fig. 7). One end portion of the bar 96 is provided with a projecting pin 98, which pin 98 mounts bracket 99 for relative angular movement thereon. A set screw 100 with a suitable wing nut thereon is provided to maintain any adjusted position. Thus desired angular position between bar 96 and the bracket 99 may be provided, and then by tightening of screw 100 such adjustment may be maintained. The bracket 99 carries a cup-shaped head rest 101 which is similar in function to the cup-shaped head rest 70. The said head rest 101 is shown in elevation in Figs. 4 and 5 and in perspective in Fig. 6.

A patient may be placed on the orthopedic table as is illustrated in Fig. 1 of the drawings. In such a position a patient will be supported at the buttocks on the sacral rest 83, legs on boards 53, trunk supported by inter-scapular support 60, and the head will be supported by either the head rest 101 or 70. Also the sling 77 and foot plates 81 may be used when desired. After a cast 84 has been applied about the head

of a patient and the cast has sufficiently set or hardened so it is desired to remove the occipital support 70 or 101, the occipital support may be angularly moved out the head cast with the contacting surface portion of the occipital support following the contour of the head of the patient, until the occipital support is removed as is best indicated in Fig. 5 of the drawings. In this connection it is to be noted that the occipital support of Figs. 1 and 3 of the drawings is removed 10 with the bracket 69 by first loosening set screw 81 and that the occipital support 101 is removed with the bracket 99 by first loosening set screw 100. While it is possible to remove an occipital support with more or less of the supporting apparatus connected with the same, it is convenient to remove an occipital support with the bracket 69 connected therewith.

From the foregoing it will now be apparent that I have provided an occipital support over which a head cast may be applied and the occipital support later removed when the head cast has reached a desired state or set or hardness, and at the same time without weakening or otherwise modifying normal or standard head casts. Also it will be apparent that if the neck of a patient is not normal but extends at an angle to one side or the other that the extension member 71 may be pivoted by loosening a bolt and nut means 72 and the angular position of the extension member 71 may be aligned with a particular angle of a patient's neck (illustrated in Fig. 7). If very minor adjustments are needed, it may be necessary to remove the stud 73 from the extension member 71 and the bracket 22. However, as I provide nut and bolt means 72, any desired adjustment of the angular relation between the extension member 71 and the bracket 22 may be provided. Next the relative angular position between the connector 94 and the shaft 93 may be made by loosening of screw 95. Also any desired angular relation between the bracket 99 and the bar 96 may obtain upon loosening of set screw 100. Thus desired angular relationships may be made to support the 45 head of a patient on a head rest 101 even though the neck of a patient is not normal so far as the angle of the head of the patient to the chest of the patient is concerned. If a head rest 101 is adjusted angularly because of peculiarities of a patient, a corresponding adjustment may be made in the angular position of the extension member 71 so that a pull provided on the head sling 77 corresponds with the alignment of the head of the patient.

From the foregoing it is apparent that either the cup-shaped head rest 70 or the head rest 101 comprises an occipital support on which the head of a patient may be supported for the application of a plastic or a plaster cast which includes a head rest having a top opening out which the head rest may be removed after the head cast is formed and has sufficiently set or hardened so that the patient can be moved without fear of injury to the head cast. The end portion of the head cast toward the patient extends slightly over the convexed curve of the occiput of a patient and thus provides all of the support that is necessary without unnecessary support on the neck of the patient and if the occipital support were to extend toward the neck of the patient it would be of a size so that it could not be removed out the usual open top which is normally left in head casts. From such location the cast of my invention extends upwardly 70

so far as the head of a patient is concerned, over said convex curved occiput and the opposite end portion of the head rest terminates in the area at the top of the head of a patient. Thus the bracket supporting member for the head rest, which may include the L-shaped bracket 69 or may include the bracket 99, bar 96 and threaded bar 93, connects with the opposite end portion of the head rest. A bracket connected with the head rest 70 and with the L-shaped bracket 69 as well as the bracket 99 and bar 96 extend away from and generally follow the plane of a head rest. Also in said construction the L-shaped bracket 69 is detachably connected with the head rest 70 while the following parts are detachably connected from each other: shaft 93, bar 96 and bracket 99 carried by head rest 101. Regardless of whether or not the construction embodying head rest 70 or that embodying head rest 101 is followed, I have provided a head rest to support a patient's head at the occiput and which head rest will not interfere with the operator in applying a head cast, the head cast may be applied or formed about the head rest and after the cast is sufficiently set or hardened so the patient may be moved, the head rest may be angularly moved so the same can be moved out of the cast and out through a usual opening which is left at the top of the head cast.

Obviously changes may be made in the forms, dimensions and arrangements of the parts of my invention without departing from the principle thereof, the above setting forth only preferred forms of embodiment of my invention.

I claim:

1. An occipital support on which the head of a patient may be supported for application of a plastic or a plaster cast which includes a head cast having a top opening out of which the head rest is adapted to be angularly removed after formation of the cast comprising a concave head rest, one end portion of which is adapted to extend over and terminate in the area of the convex curve of the occiput of a patient and the opposite end portion of which is adapted to extend toward and terminate in the area of the top of the head of a patient; and a bracket supporting member adapted to be connected to a suitable external supporting means, connected with said opposite end portion of said head rest and extending away from said head rest, whereby after formation of such cast, which includes a head cast having a top opening, the occipital support is adapted to be angularly removed generally following a path conforming to the curvature of the top of the head of a patient, said bracket supporting member being detachably connected with said head rest.

2. An occipital support on which the head of a patient may be supported for application of a plastic or a plaster cast which includes a head cast having a top opening out of which the head rest is adapted to be angularly removed after formation of the cast comprising a concave head rest, one end portion of which is adapted to extend over and terminate in the area of the convex curve of the occiput of a patient and the opposite end portion of which is adapted to extend toward and terminate in the area of the top of the head of a patient; and a bracket supporting member adapted to be connected to a suitable external supporting means, connected with said opposite end portion of said head rest and extending away from said head rest, whereby after formation of such cast, which includes a

head cast having a top opening, the occipital support is adapted to be angularly removed generally following a path conforming to the curvature of the top of the head of a patient, said bracket supporting member comprising an L-shaped member, one leg of which is substantially at right angles with said head rest and the other leg of which is substantially at right angles to said first-mentioned leg.

3. An occipital support on which the head of a patient may be supported for application of a plastic or a plaster cast which includes a head cast having a top opening out of which the head rest is adapted to be angularly removed after formation of the cast comprising a concave head rest, one end portion of which is adapted to extend over and terminate in the area of the convex curve of the occiput of a patient and the opposite end portion of which is adapted to extend toward and terminate in the area of the top of the head of a patient; and a bracket supporting member adapted to be connected to a suitable external supporting means, connected with said opposite end portion of said head rest and extending away from said head rest, whereby after formation of such cast, which includes a head cast having a top opening, the occipital support is adapted to be angularly removed generally following a path conforming to the curvature of the top of the head of a patient, said bracket member being rotatably mounted for movement about a vertical axis and being mounted for rotatable movement relative to said head rest.

4. An occipital support on which the head of

5 a patient may be supported for application of a plastic or a plaster cast which includes a head cast having a top opening out of which the head rest is adapted to be angularly removed after formation of the cast comprising a concave head rest, one end portion of which is adapted to extend over and terminate in the area of the convex curve of the occiput of a patient and the opposite end portion of which is adapted to extend toward and terminate in the area of the top of the head of a patient; and a bracket supporting member adapted to be connected to a suitable external supporting means, connected with said opposite end portion of said head rest and extending away from said head rest, whereby after formation of a cast, which includes a head cast having a top opening, the occipital support is adapted to be angularly removed generally following a path conforming to the curvature of the top of the head of a patient.
